UNITED STATES PATENT OFFICE

GEORGE HOWARD PERKINS, OF CAMBRIDGE, MASSACHUSETTS, ASSIGNOR TO WARREN BROTHERS COMPANY, OF CAMBRIDGE, MASSACHUSETTS, A CORPORATION OF WEST VIRGINIA

METHOD OF SPREADING BITUMINOUS MIXTURES

Application filed December 18, 1928. Serial No. 326,863.

The object of this invention is to provide a method whereby a bituminous mixture may be spread in a layer, of any desired depth, in such a manner that the layer will be of uniform compactness. In explanation of the specified objects of this invention which are attained as the culmination of many years practical experience in constructing roadways of all kinds made of the materials stated, the following is believed to be a fair general statement of present practices.

Bituminous mixtures used for the wearing surfaces of sidewalks roadways or the like, or for waterproofing are ordinarily composed of mineral particles coated with bituminous cement. As the function of the bituminous cement is to bind the mineral particles together after the mixture has been spread and compacted, naturally it must be both cohesive and adhesive, hence if such a mixture is subjected to but even slight pressure it becomes coherent, due to the adhesion of the bitumen coated particles to each other.

Due to this characteristic it has not been possible, by any of the means used in the past within the knowledge of applicant, to spread such a mixture in a layer which is of uniform consistency throughout, hence when such a layer is compacted by the customary means of passing a heavy roller over its surface, the resultant compacted layer is not uniform in compactness throughout, but is more dense in some spots than in others.

In the past it has been customary to convey such a bituminous mixture in suitable vehicles from point of preparation, to the point of use and there to deposit and spread it in a layer of approximately the desired depth by means of shovels and rakes or by some form of mechanical spreading machine, and then to compact the layer of means of a roller, and in places inaccessible to the roller by hand tamps or equivalent means.

When the mixture is spread by hand, that is to say, by shovels and rakes, the object of the raking is to comb the bituminous mixture so thoroughly with the tines of the rakes that the resulting layer will be not

only of uniform contour, with its surface at the desired level at all points, but also to leave it in a state of uniform compactness or of uniform looseness throughout its entire depth and area. It is impossible to thus entirely overcome with the rakes, the differences in compactness, caused by the original deposition of the mixture in shovelfuls of various volumes, striking the foundation at unequal velocities due to peculiarities in the handling of the material by particular individuals, it being obvious that a shovelful of coherent mixture dropped in a single body from a height of a foot or more will thus be compacted to a greater extent than an equal depth of the same mixture which has been cast horizontally into place, in the form of several thin layers of mixture.

All of the mechanical spreaders used for this purpose up to present date, applicant believes, are based on the principle of depositing the mixture upon the foundation in piles or in long windrows in front of a screed or template held at such a definite height above the foundation that when the screed moves forward it will push the top of the pile of mixture forward, leaving behind the screed or template a layer of mixture of the desired depth and of uniform contour. This scraping action of the screed, however, does not in any manner correct the non-uniformity of compaction existing in various parts of the pile or piles of mixture as originally deposited in front of the screed or template. In some cases the screed is given a short reciprocating motion laterally as it progresses forward and while this assists in cutting its way through the pile of mixture it does not correct the inequalities of compactness in the pile of mixture.

When a coherent bituminous mixture has been spread by either of the above methods and is then subjected to compression by rolling, the above-mentioned inequalities of compactness in various parts of the layer are corrected more or less, due to the kneading action of the roller, causing the mixture

to move horizontally back and forth to a slight extent.

However, the width of face of the wheels of the roller is greater than the average width of the spots where the mixture was deposited with little or no compaction, hence as compaction by rolling progresses the weight of the roller is carried more and more by adjacent spots which were compacted to a greater degree at time of deposition, and when these latter spots have been compressed to the fullest degree of compaction of which they are capable, they are sufficiently stable to support the weight of the roller without further diminution of their depth, hence it is impossible for the roller to deliver any further compaction to the other spots.

While it is obvious that every portion of such a layer of bituminous mixture is of greater compactness after having been rolled than before, yet if the layer was non-uniform in compactness before rolling it will still be non-uniform in compactness after rolling, though possibly the difference in relative degree of compactness of adjacent portions may be less than existed before rolling and as many portions of the layer are not compacted to the degree of which they are capable, they remain relatively porous and permeable to water, destroying the usefulness of such a mixture when spread for waterproofing purposes.

If immediately after completion a street or road with bituminous pavement surface constructed in above manner is subjected to traffic in cold dry weather, such partially compacted spots will be friable and will abrade rapidly. If the weather is both wet and cold they will absorb water and abrade more rapidly. If the weather is hot and dry, such spots will under the kneading action of vehicle wheels which are naturally narrower than those of the roller, be compacted to a depth less than that of adjacent spots which were fully compacted by the roller at time of original construction and thus form depressions in the pavement.

It is thus obvious, that even though the bituminous surface may have been of true even contour at the time the rolling was completed, it will soon develop irregularities of contour due to either abrasion or to additional compaction by traffic.

The present invention prevents the formation of such irregularities in compactness of such bituminous structures, by depositing the bituminous mixture upon the foundation, not in the form of coherent piles of various degrees of compactness, but in the form of a shower of individual, bitumen coated mineral particles or of relatively small pellets composed of a number of very small bitumen coated particles, depending upon the size of mineral particles composing the mixture.

The method constituting the present invention comprises conveying the bituminous mixture from convenient stock piles or equivalent sources of supply to the location where it is desired to spread same in a layer and to then comminute the mass of mixture into the individual bitumen coated particles of which it is composed, or at least into relatively small pellets, each composed of a number of bitumen coated mineral particles, and to drop said separated particles or pellets, in the form of a shower, upon the foundation or other surface upon which it is desired to form the layer of bituminous mixture. This deposition of individual particles or of small pellets of mixture, separately, without the application of any external pressure, produces a layer which is uniform in compactness or denseness throughout. The layer can be made of any desired depth by regulating the rate of discharge or the length of time or the number of times that the shower of particles is applied to any one spot or portion of the foundation.

Due to the adhesiveness of the bitumen coating of the mineral particles it is necessary that when the mixture is thus comminuted into its individual particles or into relatively small pellets of same, that they be not permitted to again agglomerate before deposition on the foundations, hence whatever machine is used to thus comminute the mixture, it must travel over the foundation or other surface upon which the layer is to be formed, so that as the individual particles or pellets emerge from the machine they will fall in a shower directly upon the surface or foundation upon which the bituminous layer is to be formed.

I am aware that layers of mixtures may be formed by the use of so-called pneumatic guns or nozzles, whereby the bituminous mixture is ejected by air pressure from a nozzle in the form of a spray or stream. In such cases the particles travel at considerable speed and strike the surface, upon which the layer is to be formed, with considerable force, thus compacting the layer while it is being formed, and it is not practicable by that method to form a layer which is uniform in depth. Such pneumatic devices, however, will only handle mixtures which are practically non-coherent at atmospheric temperature, therefore such devices are not applicable for the purpose of the present invention which is intended for use with bituminous pavement and sidewalk mixtures that are so adhesive and coherent that when transported in vehicles of ordinary size the mixture will agglomerate under its own weight and when dumped from the vehicle will not fall apart into the individual particles of which it is composed as a load of sand would do.

I have found that the method of spreading or depositing bituminous mixtures constituting this invention can best be carried out by use of a machine such as shown in 5 the drawings attached hereto.

It is understood that this present application is intended to cover the method described and not to cover the machine. Application for a patent on the machine itself 10 is about to be filed in the Patent Office jointly by Robert C. Shoemaker of Philadelphia, Pennsylvania, and myself.

Figure 1 of the accompanying drawing is a side view of the machine, and

15 Figure 2 is a rear view.

The numbers indicate the same parts of the machine in both views.

The essential parts of the machine are the hopper or receptacle A in which the bituminous mixture is carried. The bottom of the hopper is closed by the disintegrator B which consists of a chain belt which is the same width as the bottom of the hopper and which bears a series of staggered projections 20 *b* on its upper side. This belt is driven by the sprocket wheel C which in turn, is driven by a motor E through the sprocket chain *e* controlled by suitable mechanism not shown. The various parts of the machine 25 are supported on the framework F which is carried by the large wheels G which wheels may be driven in either direction, and which in turn are driven by the motor through transmission mechanism of any 30 common construction which contains facilities for speed changes, clutch, reverse mechanism, and means for readily guiding the machine while under power.

By the means of the mechanism it is possible 35 to cause the machine to proceed in either direction at any desired speed within a considerable range, also to operate the disintegrator B independently of the wheels, so that it is possible to disintegrate and deposit the mixture in the form of a shower 40 of separated coated particles, no matter whether the machine is stationary or moving in either direction. It is also possible to transport a hopperful of mixture without 45 running the disintegrator.

The bituminous mixture in the hopper 50 rests with its full weight upon the disintegrator B and when this is driven rapidly, the projections upon the upper side of the disintegrator belt, tear the mixture apart 55 into small particles and carry particles forward and past the end of the adjustable gate "D" where it is thrown off the disintegrator belt by the action of centrifugal force and 60 is showered upon the foundation or other surface upon which the mixture is to be spread. The depth of the layer may be regulated by varying the opening of the adjustable gate "D" and by varying the speed of 65

translation of the machine through varying the speed of revolution of the wheels "G".

The speed of the disintegrator may also be varied but preferably is that which will develop just sufficient centrifugal force to 70 throw the mixture off of the disintegrator chain as it passes the gate "D". It is found advantageous to construct the gate D of a number of spring fingers *d* arranged side by side as illustrated in Figure 2, in order to 75 avoid injury to the machine through the presence of adventitious material such as large stones.

What is claimed is:—

1. The method of spreading bituminous 80 paving mixtures to obtain uniform compactness of the same when being compressed which comprises first comminuting said mixture in transit to provide separated bitumen coated particles and then immediately 85 depositing said particles while still separated upon a foundation in the form of a layer of uniform density throughout.

2. The method of spreading bituminous 90 paving mixtures to obtain uniform compactness of the same when being compressed which comprises comminuting said mixture to provide separated bitumen coated particles and then depositing the separated particles upon a foundation in the form of a 95 shower of uniform density and advancing the shower over the foundation.

3. The method of spreading bituminous 100 paving mixtures to obtain uniform compactness of the same when being compressed which comprises comminuting said mixture to provide separated bitumen coated particles, then depositing said particles upon a foundation in the form of a shower and varying the rate of deposit of the shower. 105

In testimony whereof I affix my signature.
GEORGE HOWARD PERKINS.
